UNITED STATES PATENT OFFICE.

CHARLES W. BAIRD, OF MILLERSBURG, IOWA.

SWEEP-MILL.

SPECIFICATION forming part of Letters Patent No. 739,373, dated September 22, 1903.

Application filed March 15, 1902. Serial No. 98,345. (No model.)

To all whom it may concern:

Be it known that I, CHARLES W. BAIRD, a citizen of the United States, residing at Millersburg, in the county of Iowa and State of Iowa, have invented certain new and useful Improvements in Sweep-Mills, of which the following is a specification.

The invention relates to that class of sweep-mills commonly used for grinding grain and operated by means of one or more sweeps to which draft-animals are attached, and the draft-animals travel around the sweep-mill in operating it. In machines of this class it has been customary to have the grain carried to the machine by the operator and the product of the machine carried away by the operator, and obviously the carrying of the grain to and from the machine must be accomplished without interfering with the movements of the draft-animals, and it is obviously quite difficult to handle large quantities of grain by a machine of this class, because the operator and the draft-animals will interfere with the movements of each other very materially.

The objects of my invention are to provide means of simple, durable, and inexpensive construction, said means to be operated by the machine for conveying grain from a point outside of the path of travel of the draft-animals to the machine and for conveying the product of the mill from the machine to a point of discharge beyond the path of travel of the draft-animals, so that the capacity of the mill may be very materially increased on account of the ease and speed with which the operator may handle the grain, so that the draft-animals need not be stopped and started and the mill can be run at its full capacity, and, furthermore, the capacity of the mill may be very materially increased by applying two sweeps thereto, which sweeps extend in opposite directions from the mill, so that two independent teams of draft-animals may be attached to the mill. This obviously would be impracticable where the operator had to carry grain to and from the mill.

A further object is to provide means for conveying grain to the mill by employing a conveyer located above the draft-animals and capable of being moved both vertically and

horizontally, so that the conveyer for carrying grain to the mill may be located at any point relative to the grain-supply and to the discharge-chute.

55

My invention consists in certain details in the construction, arrangement, and combination of the various parts of the device whereby the objects contemplated are attained, as hereinafter more fully set forth, pointed out in my claims, and illustrated in the accompanying drawings, in which—

Figure 1 shows a side elevation of a complete mill with my improvements applied thereto as required for practical use. Fig. 2 shows a vertical sectional central view through the mill with my attachments applied thereto.

Referring to the accompanying drawings, I have used the reference-numeral 10 to indicate the base of the mill. Near the top of this base is a cross-piece 11, to which an upright shaft 12 is attached.

The numeral 13 indicates a rim having internal cog-teeth 14, and this rim is rotatably mounted, and a sweep 15 is attached thereto.

The numeral 16 is used to indicate a number of pinions supported upon the bolts 17 and these pinions and in mesh with the cog-teeth 14.

Mounted upon the shaft 12 is a pinion 18, meshed with the pinions 16. Obviously as the rim 13 is rotated the pinions 16 will operate to impart a rotary motion to the pinion 18, and this pinion 18 is connected with the 85 rotatable grinding member 19.

The numeral 20 indicates a stationary rim supported upon the bolts 17 and resting on top of the rim 13, and this stationary rim supports the stationary grinding member 21 and also supports the hopper 22.

Formed on or fixed to the stationary grinding member 21 is a central hub 23, and this hub is internally screw-threaded, and a rod 24 passes through it and is connected with the 95 rotary grinding member 19 in such a manner that a movement of the rod 25 will vertically adjust the rotary grinding member 19.

The parts just described are of ordinary construction and are of the kind now in common use. Hence a detailed description of its operation and specific construction is con-

80

sidered unnecessary, my invention consisting only in attachments to be applied to machines of this class.

The reference-numeral 25 is used to indicate a rim supported upon the legs 26, which are attached to the rim 13. The upper face of the rim 25 is provided with cog-teeth 27 for purposes hereinafter made clear. The numeral 28 indicates a rim secured to the under surface of the rim 13, and the lower surface of the rim 28 is provided with cog-teeth 29.

Mounted in the base 10 is a shaft 30, having at one end a cog-wheel 31, meshed with the tooth-rim 29. In the said base is a conveyer-chute 32, designed to receive the product of the mill, and fixed to the shaft 30 are the sprocket-wheels 33, over which the sprocket chain conveyer 34 passes. This conveyer serves to convey the product of the mill in a direction lengthwise of the chute 32. At the outer end of the chute 32 is a conveyer 35, leading upwardly to a discharge-chute 36. Obviously the chute 32 may rest upon the ground-surface, and the draft-animals may step over it when operating the mill. The said chute and conveyers may be of any ordinary construction, and hence a detailed description is thought unnecessary.

Mounted upon the hub 25 is a frame 37, which frame serves to support the uprights 38, and these uprights are attached at a point above the hopper to the beams 39, and these beams support a platform 40, upon which the driver of the draft-animals may stand. Fixed to the upper ends of the uprights 38 is a stationary shaft 41, and depending from this stationary shaft 41 are the arms 42. In the lower ends of these arms I have mounted a stationary shaft 43, and rotatably mounted upon this shaft 43 is a cog-wheel 44 in mesh with the teeth 27 of the rim 25. Fixed to the hub of the cog-wheel 44 is a sprocket-wheel 45, and this sprocket-wheel 45 is connected with a similar wheel 46 on the shaft 41 by means of the sprocket-chain 47, and fixed to the hub of the sprocket-wheel 46 is another sprocket-wheel 48, upon which a sprocket-chain 49 is mounted.

From the foregoing description it is obvious that as the sweep-mill is operated by the draft-animals motion will be imparted to the sprocket-chain 49.

The numeral 50 indicates a brace connecting one of the arms 42 with the beams 39 to support the arms in their vertical position at all times.

I shall next proceed to a description of the conveyer by which the grain is introduced from a point outside of the path of travel of the draft-animals into the hopper 22.

The numeral 51 indicates a trough supported at one end upon the vertically-adjustable legs 52. At one end of the trough I have supported a sprocket-wheel 53 and at the other end a sprocket-wheel 54, and over these wheels a sprocket conveyer-chain 55

passes, thus scraping the grain in the trough 51 toward the discharge end thereof.

The numeral 56 indicates a second conveyer-trough rigidly secured at one end to the trough 51 by means of the brackets 57. This trough 56 is provided at its ends with the sprocket-wheels 58 and 59, and over these wheels the conveyer-chain 60 passes, thus carrying the grain discharged from the trough 51 the entire length of the trough 56 to the discharge end thereof. The discharge end of this trough 56 is supported upon the arms 61, which arms are attached to the beams 39 and to the braces or uprights 38. Pivoted to the discharge end of the trough 56 is a chute 62, with its discharge ends arranged directly above the hopper 22. I drive the sprocket-wheel 59 by means of the chain 49, passing over a sprocket-wheel 63, which wheel is attached to the sprocket-wheel 59 to rotate in unison therewith.

It is obvious that the conveyer for carrying away the product of the mill is fixed in its relation to the mill proper, and the mill must be so placed as to discharge its contents at the desired point. However, the means for carrying grain to the mill may be moved in a horizontal plane throughout a complete circle, and hence the grain may be fed to the machine from any point. Furthermore, the receiving-trough 51 may be readily and quickly raised and lowered to any desired height by adjusting the legs 52, and this may all be done without any adjustment of the conveying mechanism. The troughs 51 and 56 must, however, always be high enough to permit the draft-animals to pass under them.

One of the important features of my invention consists in supporting the frame 37 upon a hub 23, and by this arrangement I gain a number of important advantages. First, it provides means whereby the conveyer for carrying grain to the hopper may be moved in a horizontal plane to any point around the machine, and, further, some sweep-mills have the lower grinding member stationary while the upper one rotates, and obviously by providing this kind of a connection the upper grinding member may rotate without changing the operation or function of my device for carrying grain to the sweep-mill. Furthermore, my invention may be applied in the nature of an attachment to any of the ordinary sweep-mills now on the market.

I am aware that means have been provided heretofore for carrying the product of the mill to a point of discharge beyond the line of travel of the draft-animals. Therefore I do not claim this part of the device broadly, nor do I make any claim on the construction of the mill proper.

Having thus described my invention, what I claim, and desire to secure by Letters Patent of the United States therefor, is—

1. The combination with a sweep-mill, having a toothed rim and a sweep for rotating

it and also having stationary and rotatable grinding members, of a conveyer having one end supported on the stationary grinding member, means for supporting its other end 5 at a point beyond the path of travel of the sweep, said conveyer operated from the toothed rim and discharging into the mill.

2. The combination with a sweep-mill, having a toothed rim and a sweep for rotating it and also having stationary and rotatable grinding members, of a cross-piece 37 mounted on the stationary grinding member, braces 38 fixed to said cross-piece, a trough supported at one end upon said braces above 15 the grinding-mill, means for supporting the other end of said trough and a conveyer in said trough operated from the toothed rim and discharging into the mill.

3. The combination with a sweep-mill, having a toothed rim and a sweep for rotating it and also having stationary and rotatable grinding members, of a platform rotatably supported upon the stationary member, a rotatable pinion supported from the platform 25 and meshed with the said toothed rim, a conveyer-trough connected with the platform and with the stationary grinding member at one end, means for supporting the other end of the conveyer-trough, a conveyer in the 30 trough and means for driving the conveyer from said pinion, for the purposes stated.

4. The combination with a sweep-mill, having a toothed rim and a sweep for rotating it and also having stationary and rotatable 35 grinding members, of a frame rotatably

mounted upon the stationary grinding members, braces attached to said frame and projected upwardly, a number of conveyer-troughs connected with each other, the inner end of the inner trough supported by means 40 of said braces, legs for supporting the outer end of the outer trough, a pinion supported by the frame and meshed with the toothed rim, conveyers in said troughs, and means for driving said conveyers from the said pinion, 45 for the purposes stated.

5. The combination with a sweep-mill, having a toothed rim and a sweep for rotating it and also having stationary and rotatable grinding members, of a frame rotatably supported upon the stationary grinding members, a platform connected with said frame, a pinion carried by said frame and meshed with the toothed rim, a conveyer-trough 51, 50 legs for supporting its outer end, a conveyer-trough 56 beneath the inner end of the conveyer-trough 51, brackets connecting said troughs, braces for supporting the inner end of the trough 56 connected with the said frame, a trough 62 connected to the inner 60 end of the trough 56 and discharging into the mill, scraping-conveyers in the troughs 51 and 56 and means for driving the conveyers from the said pinion, substantially as and for the purposes stated.

CHARLES W. BAIRD.
